DESIGN FOR A COMBINED SUPPORTING
BRACKET AND SHIELD FOR A CONDIMENTS
CONTAINER OR SIMILAR ARTICLE

Lauretta S. Madda, Chicago, Ill.

Application July 7, 1938, Serial No. 78,319

Term of patent 7 years

To all whom it may concern:

Be it known that I, Lauretta S. Madda, a citizen of the United States, residing at Chicago, in the county of Cook and State of Illinois, have invented a new, original, and ornamental Design for a Combined Supporting Bracket and Shield for a Condiment Container or Similar Article, of which the following is a specification, reference being had to the accompanying drawing, forming part thereof, wherein Fig. 1 is a perspective view of a combined supporting bracket and shield for a condiment container or similar article embodying my design; Fig. 2 a top plan view and Fig. 3 a bottom plan view of the same.

I claim:

The ornamental design for a combined supporting bracket and shield for a condiment container or similar article, as shown.
